UNITED STATES PATENT OFFICE.

ALEXANDER DICKSON, OF BROOKLYN, NEW YORK

WALL CONSTRUCTION.

1,301,110.

Specification of Letters Patent. Patented Apr. 22, 1919.

Application filed May 23, 1918. Serial No. 236,148.

To all whom it may concern:

Be it known that I, ALEXANDER DICKSON, a citizen of the United States, residing at Brooklyn, in the county of Kings and State of New York, have invented certain new and useful Improvements in Wall Construction; and I do declare the following to be a full, clear, and exact description of the invention, such as will enable others skilled in the art to which it appertains to make and use the same.

My invention relates to improvements in plastic walls and more particularly to partition walls, the object being to provide a wall of this class which may be constructed much more easily and inexpensively than those now commonly used, the arrangement being such as to cause the walls to be substantially crack proof, sound proof, vermin proof, rat proof and fire proof.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a side elevation of a wall constructed in accordance with my invention, a portion of the plastic being removed to more clearly disclose the arrangement of studs and laths;

Figs. 2 and 3 are sectional views on the planes indicated by the lines 2—2 and 3—3 respectively of Fig. 1;

Fig. 4 is a detail perspective view showing the construction of one of the studs;

Fig. 5 is a view similar to Fig. 2 but illustrating a slightly different form of construction;

Fig. 6 is a detail perspective view of the stud shown in Fig. 5;

Fig. 7 is a horizontal section showing the manner in which the partition terminates at a door frame or the like;

Fig. 8 is a detail side elevation showing the manner in which the lath ends may be wedged in place upon the studs;

Fig. 9 is a view very similar to Fig. 8 but illustrating the way in which metal reinforced laths may be secured to the studs by their reinforcing means;

Fig. 10 is a duplicate of Fig. 1 with the exception that it shows a different form of stud and another arrangement of laths;

Figs. 11 and 12 are sectional views on the planes indicated by the lines 11—11 and 12—12 respectively of Fig. 10; and

Fig. 13 is a perspective view of one of the 60 studs shown in Figs. 10, 11 and 12, illustrating a number of the laths in dotted lines. In the drawings above briefly described, the numerals 1 (Figs. 1 to 9) designate angle iron studs extending between a floor F and 65 ceiling C, the lower ends of said studs being shown as secured in place by L-irons 2. Metal yokes 3 preferably pass through openings in the upper ends of the studs to secure them to the ceiling. One flange of each 70 stud 2 is provided with a plurality of vertically spaced slots 4 which may either be slightly inclined as shown in Figs. 5 and 6, or truly horizontal as depicted in Figs. 2 and 4. In all of these figures the slots 4 are 75 shown opening through the free edge of the flange in which they are formed, but in some instances both ends of the slots could well be closed.

The slots 4 are preferably of sufficient width 80 to receive the overlapped ends of the horizontal laths 5 as seen for instance in Figs. 1 and 8, and if desired the lath ends may be wedged in place as illustrated in Fig. 8, by means of suitable wedges 6. In some instances, the slots 4 could be spaced different distances and formed of less width, so that the laths could be disposed in staggered relation and only one lath end received in each slot. Also, if metal reinforced laths such as 90 5^a of Fig. 9 are to be used, the reinforces 7 thereof may well extend from the ends of the laths to rest upon and be bent around the lath supports formed between the notches 4. Also, if desired, strips of metal lath or the like 95 8 may be secured by wires or the like 9 to the studs 1 to prevent accidental removal of the laths 5 from the notches 4 (see Fig. 5).

Fig. 7 discloses the manner in which the 100 partition wall may terminate at a door frame or the like. In this figure the numerals 10 designate a pair of vertically disposed grounds to which the adjacent stud 1 is secured by nails 11 or any other preferred 105 fastening means, said grounds being in turn nailed or otherwise fastened to a vertical buck 12 disposed therebetween. The frame 13 is secured to this buck, and the trim 14 is secured to the grounds 10.

In order that the chair board or wash board 15 may be nailed in place as required,

a horizontal ground 16 is secured in the notches 4 at the lower ends of the studs 1 as featured in Figs. 1 and 2, the nails 17 being driven through the boards 15 into said 5 ground as shown.

After assembling the frame structure consisting of the vertical studs and the laths, and securing the door frames and the like in place, but before the trim 14 and the 10 boards 15 are applied, a scratch coat of plaster is worked into the spaces between the laths 5. A brown coat is then applied to the scratch coat and troweled over the edges of the laths and studs, and finally a finishing 15 coat is applied to each side of the partition producing substantially a monolithic wall 18.

The wall constructed as above described will be substantially fire proof, sound proof, 20 will not crack, will afford no nesting places for mice and rats, and will be vermin proof. In addition to these advantages, the wall may be constructed at less expense than those 25 now commonly used, due principally to the fact that the studs 1 and laths 5 may be set farther apart. Another feature which adds to the saving is the fact that the laths need not be nailed in place at several points as is now necessary, it being simply necessary to 30 insert them in the slots provided for the purpose. Furthermore, old laths may be used if desired without removing the previously used nails therefrom, since these nails will be of advantage in keying the mortar to 35 the laths. Additional keying may be had by forming slots or the like 19 in the flanges of the studs 1 as shown.

In Figs. 10, 11, 12 and 13, the studs 1^a are formed of flat metal bars, said bars being 40 formed with horizontal slots 4^a which do not open through either edge thereof, said slots being only of sufficient size to receive one end of the laths 5^b, although it is to be understood that they could well be of larger sizes

to permit application of the laths in the 45 same manner as above set forth. The plastic 18^a is applied in the same manner as above set forth and the wall produced by the complete structure will possess the same advantages, further explanation being there- 50 fore superfluous.

From the foregoing, taken in connection with the accompanying drawings, it will be obvious that although my invention is of simple and inexpensive nature, it will be 55 of great advantage, and since probably the best results are obtained from the several details shown and described, they are preferably employed. Within the scope of the invention as claimed however, considerable 60 latitude is allowed for making such minor changes as occasion may dictate.

I claim:

1. A wall comprising a plurality of studs having vertically spaced horizontally disposed lath supports, a single vertical series of laths extending horizontally between said studs and lying flat upon said supports, said laths substantially equaling said studs in width, and a plastic filler in the spaces between the laths and troweled over the edges of said laths and said studs. 65 70

2. A wall comprising a plurality of studs having horizontal slots with their ends disposed at the inner and outer edges of said 75 studs, a single vertical series of laths extending horizontally between said studs with their ends received in said slots, and a plastic filler in the spaces between the laths and troweled over the edges of said laths and 80 said studs.

In testimony whereof I have hereunto set my hand,

ALEXANDER DICKSON.

Witnesses:
